(57) **CLAIM**

The ornamental design for a welcome/goodbye mat, as shown and described.

DESCRIPTION

FIG. 1 is a top plan view of a welcome/goodbye mat, showing my new design.

FIG. 2 is another top view of the welcome/goodbye mat of FIG. 1; and,

FIG. 3 is a front elevation view of the welcome/goodbye mat of FIG. 1.

In the drawings, the broken lines define the boundaries of the claimed design and form no part thereof.
